WASHING MACHINE STAND

Bernhart A. Benson, Chicago, Ill., assignor to
Chicago Electric Manufacturing Company,
Chicago, Ill., a corporation of Illinois

Application May 6, 1938, Serial No. 206,386

1 Claim. (Cl. 248—150)

The present invention relates to a stand for an appliance and more particularly to a washing machine stand.

The present invention more specifically comprehends the provision of a combination washing machine and supporting stand for positively engaging the washing machine and supporting it in predetermined position above the floor, the washing machine and stand being physically separable by merely lifting the machine from the stand, but providing a firm, adequate and rigidly supported unit when interconnected. Machines for washing clothes and the like have heretofore conventionally comprised relatively bulky parts, requiring a large amount of permanent storage space and demanding a permanent support which will elevate the operative parts above the floor a convenient distance for control by the operator.

It is an object of the present invention to provide a combination as above, employing a relatively compact washing machine and collapsible stand, which stand is capable of being folded so that all the parts thereof reside in a substantially flat plane and accordingly occupy but a relatively small space for storage in a closet or any other convenient place in the home.

Another object of the present invention is to provide a collapsible stand as above, having portions extending upwardly about the washing machine to center the same, the upwardly extending portions cooperating with rubber or other soft or resilient frictional means to provide a cushion contact with the machine for the purpose of preventing damage to the surface finish thereof.

Still more specifically the present invention comprehends the provision of a combination collapsible stand and washing machine wherein the latter element of the combination is a washing machine of the type having a drive means, such as a motor, mounted thereon. Devices of this class, and particularly those having drive means mounted centrally or axially thereof, normally in operation result in the creation of forces due to the reaction of the drive means and the agitating effect of the washer, which tend to rotationally shift the machine and to disengage it from its support. These forces may also have a tendency to cause many types of collapsible stands to fold or collapse during operation of the machine, with obviously unfortunate results.

It is accordingly an object of the present invention to provide a stand which while being freely collapsible to a substantially flat unit, nevertheless comprises resilient supporting means engaging the washing machine for supporting and po-

sitioning the machine, the resilient supports being frictionally active so that when the washing machine is operatively positioned thereon a sufficient frictional resistance will be set up to prevent the machine from moving or creeping with respect to the stand, the frictional interengagement also tending to lock the stand to the machine to the extent of preventing unauthorized collapse of the stand.

Among the additional objects of the present invention are to provide a folding stand as above, which is light in weight, yet durable and simple to manufacture, and a washing machine stand which is adapted frictionally to engage the floor so that it will not shift or creep under the influence of the forces set up in service.

Numerous other objects, advantages and inherent functions of the invention will become apparent as the same is more fully understood from the following description when taken in connection with the accompanying drawing.

Referring to the drawing:

Fig. 1 is a perspective view of a washing machine stand constructed in accordance with the present invention;

Fig. 2 is a perspective view the same as Fig. 1, showing the parts of the stand folded or collapsed to a relatively flat position;

Fig. 3 is a detail elevational view showing a washing machine operatively supported upon the stand;

Fig. 4 is a detail elevational view taken on the line 4—4 in Fig. 1;

Fig. 5 is a detail perspective view showing the juncture and manner of interlocking of the relatively movable portions of the stand; and

Fig. 6 is a sectional elevation taken on the line 6—6 of Fig. 5.

Referring more specifically to the drawing, wherein the present invention is illustrated in detail, Figs. 1 and 2 illustrate an assembly comprising a preferred illustrative stand constructed in accordance with the present invention. This stand comprises in general a pair of leg sections 10 and 12, respectively, pivoted together by means of pivots 14 and 16. Each of the leg sections comprises a pair of upstanding tubular members 18 providing legs for the stand and being joined by transversely extending straps 20 and 22, respectively. It will be noted that the ends of the strap members are engaged by machine bolt fastening means 26 passing through suitable aligned apertures in the tubular leg members 18, as clearly shown in Fig. 4. In accordance with this construction, therefore, the machine bolts 55

26 secure each pair of legs 18 and transverse members 20 together as a unit. Additional means is provided for rigidifying each supporting leg section and comprises angle members 28 5 formed of a strap of metal having its ends bent as at 30 and 32 to lie against the surface of the leg members 18 and the upper surface of the transversely extending connecting straps 22, respectively. The upper connecting portion 30 is 10 fastened to the respective leg 18 by means of a machine bolt 34, whereas the lower connecting portion 32 is interconnected with the strap 22 by means of a rivet 36. The relatively pivotal leg sections are interengaged, as clearly shown 15 in Figs. 1 and 2, with one leg section having its upper transversely extending strap 20 arranged above the corresponding strap 20 on the other leg section, but having its lower strap 22 below the strap 22 of the other leg section.

20 The pivots 14 and 16 may comprise rivet members 38 so applied as to provide predetermined frictional engagement between the respective leg sections in order to maintain the parts firmly together, while permitting manual adjustment to 25 the desired relative position. It is to be noted that the lower transversely extending strap 22, see Fig. 6, is deformed upwardly about the region of the rivet 38, as at 40, to provide an embossment, for the purpose of providing a carefully 30 predetermined area of frictional contact between the members 22 which are accordingly normally spaced a small vertical distance in all relative positions. The upper transversely extending straps 20 are pivoted together in the same manner, as a result of which the leg sections 10 and 12 while being firmly secured together for relative rotation, are nevertheless free from any possibility of binding or any other troublesome and 35 undesired interengagement which might interfere with the facility by which the parts may be normally either operatively engaged or folded.

Stop means for determining the extended operative position of the leg sections is shown more clearly in Figs. 5 and 6 and comprises a clip 42 45 of U-shaped section having short, upstanding side walls 44 terminating at opposite ends in elevated tabs or projections 46. Attention is directed to the fact that each of the tabs is provided with a forwardly extending finger 48 extending toward the central portion of the strap 22 to which they are attached, and spaced from the upper edge of the corresponding upwardly extending wall 44 to provide rectangular grooves or notches 50. It is important to note that this 50 stop clip member 42 is mounted centrally of the lowermost transversely extending strap 20 by means of welding, not shown. The upwardly extending walls 44 terminate substantially at the level of the upper surface of the lower transversely 55 extending strap 22 just mentioned, so that the upper strap 22 pivoted thereto may be rotated to move freely thereover and to be guided into the grooves or notches 50 formed by the guide fingers 48. When relatively arranged in this 60 position, as shown in Figs. 1 and 6, each pair of straps 20 and 22 will be arranged substantially at right angles to provide a four-legged stand.

If it is desired to collapse or fold the stand, the leg section indicated by the numeral 12 may 65 be rotated in a clockwise direction with respect to the other leg section 10 to bring the assembly to the position shown in Fig. 2, wherein the parts all lie in a substantially flat plane.

All of the tubular leg members 18 are enclosed 70 at either end by means of relatively soft or re-

silient buffer members 52 having corrugated internal surfaces 54 adapted to frictionally grasp the surface of the tubular members to retain the latter securely in place. It will be seen that the lower members 52 provide foot portions for 5 the legs 18. These foot portions are of great importance, since they mount and position the stand fixedly with respect to the floor, regardless of the vibration or inertia forces set up in the 10 operation of the washing machine to be described hereinafter more in detail. The upper transversely extending straps 20 serve to directly support the washing machine, as shown more clearly in Fig. 3, and to this end have mounted on their upper surfaces the resilient 15 buffer members 56, secured in place by machine screws 58.

As clearly shown in Fig. 3, a washing machine, indicated generally by the reference numeral 60, 20 may be positioned directly upon the resilient buffer supports 56. The particular washing machine shown in Fig. 3 for purposes of illustration comprises a relatively portable structure of the type disclosed in my copending application, Serial No. 175,450, filed November 19, 1937. This construction comprises a cylindrical tub or container 62 adapted to contain the articles to be washed, and a cover 64 having the driving mechanism mounted thereon, as at 66. It will be understood that an agitator or equivalent means, not shown, 25 is arranged interiorly of the container 62 to produce an automatic washing action. Devices of this class, being relatively light, may be prone to displacement under the influence of forces set up by the reaction of the moving parts and the 30 agitating effect of the washer. In accordance with the present invention, however, it will be seen that the washing machine 60 is firmly positioned within the space between the upper ends 35 of the vertical leg members 18. The side walls 40 of the machine, however, are spaced from the legs 18 by the resilient buffers 52 on their upper ends so that at no time can the surface of the machine be brought into contact with the relatively hard portions of the stand to damage the 45 surface of either of the structures. When positioned as shown in Fig. 3, the container 62 can not be displaced sidewise in any direction with respect to the stand. It is accordingly at all times rigidly positioned and spaced a predetermined 50 distance from the floor.

When it is desired to disassemble the parts for storage, the washing machine may be freely physically separated by merely lifting the tub vertically upwardly away from the stand. The washing machine 60, as disclosed in my aforementioned copending application, may then be stored in a space substantially no greater than that occupied by the outer container or tub 62, while the stand may be folded to the position shown in 60 Fig. 2 and conveniently located in a closet or any other storage space.

Attention is directed to the fact that when the stand is operatively positioned with respect to a washing machine for support thereof, inadvertent folding or collapsing of the stand is impossible, due to the frictional engagement of the resilient members 52 and 56 with the surface of the container 62. In other words, it is contemplated in accordance with the present invention 70 that the members 52 and 56 comprise a resilient material, such as rubber, for example, having frictional properties, so that when firmly contacted with a fixed surface they will remain in prearranged spaced position.

5 The present invention provides a washing machine assembly which rigidly and securely supports the washing machine during use but which may be readily disassembled to occupy very little space. While for purposes of illustration the present invention shows the employment of a particular form of washing machine, it will be apparent from the above disclosure that various other washing machines and appliances of this 10 class may be employed in substantially the same manner.

15 Changes may be made in the form, construction and arrangement of the parts without departing from the spirit of the invention or sacrificing any of its advantages, and the right is hereby reserved to make all such changes as fairly fall within the scope of the following claim.

The invention is hereby claimed as follows:
In a stand for a portable washing machine

5 comprising a pair of leg sections having spaced, parallel legs joined at points spaced a substantial distance from the extremities thereof by transversely extending frame members, pivot means interconnecting said frame members for permitting relative rotational movement of the sections from a folded position wherein the sections reside in a generally flat plane to an expanded position, said frame members forming a support for the machine with leg extensions projecting thereabove; 10 means for engaging a washing machine placed thereon to hold the said sections in said expanded position comprising resilient cap members embracing said extensions of said legs, each of said cap members projecting a substantial distance laterally of the leg to frictionally engage the machine for holding the frame against relative rotational displacement.
